UNITED STATES PATENT OFFICE.

JOHN A. GEBHARD AND ROBERT N. BARLOW, OF DETROIT, MICHIGAN.

DUPLICATING COUNTER-CHECK BOOK.

SPECIFICATION forming part of Letters Patent No. 314,662, dated March 31, 1885.

Application filed March 14, 1884. (Model.)

To all whom it may concern:

Be it known that we, JOHN A. GEBHARD and ROBERT N. BARLOW, of Detroit, county of Wayne, and State of Michigan, have invented a new and useful Improvement in Duplicating Counter-Check Books, as set forth in the following specification.

In order to aid others skilled in the art to which our invention belongs to make and use it, we will proceed to describe its construction and operation, with reference to the several drawings, forming a part of this specification, in which—

Figure 1 is a perspective of our invention as partly open. Fig. 2 is a longitudinal section through the same, having the folding leaves or contents removed therefrom.

In the drawings, A represents the common cover, which is flexible at the center. The right-hand portion of the cover is provided with two pockets, e e', having their opposite edges and ends closed, with their facing edges open. These pockets are designed to hold the memorandum-sheet E in its proper place, and when this sheet is filled up, it may be removed by drawing up at the center, when the ends of said sheet will draw out of the pockets e e'. A new sheet may then be inserted by pressing the ends into the pockets, which are made sufficiently large to receive them.

On the inside, at the left-hand of the cover, we place a yearly calendar, F, for ready reference to day and date. The calendar may be secured to the cover in any suitable manner. We attach to the left-hand portion of the cover a fly-leaf, A'. (See Fig. 2.) This leaf is made of thick card-board or like material, and is hinged to the cover A by two strips of facing or thin leather, the one G being pasted into the flexible part G² of the cover, which helps to strengthen the cover at its bending-point. The strip G' is pasted onto the left-hand portion of the cover A, thus forming a strong and double hinge for the fly-leaf A'.

To the free end of the fly-leaf we attach a box or pocket, D, being open on the inner face. (See Fig. 2.) This pocket is made of stiff material, having its back and ends closed. The pocket D is intended to hold the sheets B B' in their proper place, also the carbon sheet C, as shown in Fig. 1. The sheets B B' used in books of this class are put up in pack-

ages of a desired number, being secured together at one end, and are called "blocks" or "tablets." We perforate the sheets for separation at b b'; but they may be perforated one or more times. The sheets B B' being secured together, we insert the portion from the line of perforation b outward within the pocket D. This pocket we make small enough so that the sheets B B' have to be forced into it, and are then held by friction. By this arrangement we are able to dispense with rubber bands, such as are now used. The rubber bands are constantly stretching, becoming loose, working off of the cover, and frequently breaking, causing trouble and annoyance when we insert the sheets.

Within the pocket D we place the common carbon sheet C on top, as shown in Fig. 1, it being also held in place by the pocket D.

It will be observed that as the sheets B are torn from the book, the quantity or number of leaves do not diminish within the pocket D, as the leaves or sheets B are separated at the line of perforation b. By this arrangement, when the sheets have all been torn from the book, the pocket D will be full, containing the stub ends of said sheets. When the stub end has been removed, the book may be again re-filled, as before stated.

This book is designed for commercial purposes in the manner and for the following reasons: The operator having sold a bill of goods or the like, takes the book from his pocket, and, placing it upon the counter, folding the sheet B' over the carbon sheet C, with a pencil makes a statement for the purchaser on sheet B'. This is copied onto sheet B by the carbon sheet C, all of which is old. The sheets are then separated. The sheet B' is given to the purchaser of goods, and sheet B is retained by the firm. To obtain the day and date of the year, turn the fly-leaf A' toward you, when the calendar will be in full view. To make an entry upon the memorandum-sheet E, turn the sheets B' from you, when it will be readily reached.

It will be observed that when the cover A is folded, the contents of the book is fully protected.

Having thus described our invention in the most exact terms that we can give, what we claim as new, and desire to secure by Letters Patent, is—

1. A duplicating counter-check book composed of the cover A, flexible at the center, said cover having pockets e e' and memorandum-sheet E, with a yearly calendar, arranged as specified, and a fly-leaf, A', hinged to said cover, said fly-leaf having the pocket D at its free end for supporting the leaves and carbon sheet, as set forth.
- 5 2. A duplicating counter-check book hav-

ing a cover flexible at the center, with a fly-leaf hinged thereto, said fly-leaf having a pocket at its free end for holding the detachable sheets as specified.

JOHN A. GEBHARD.
ROBERT N. BARLOW.
